United States Patent

Des. 239,967
Patented May 18, 1976

239,967

FLOODLIGHT

Robert Lowell Ewing, Newark, Ohio, and Mitchell Bobrick, Redondo Beach, Calif., assignors to Johns-Manville Corporation, Denver, Colo.

Filed Apr. 25, 1974, Ser. No. 463,931

Term of patent 14 years

Int. Cl. D26—03

U.S. Cl. D48—20 K

FIG. 4.

FIG. 5.

Fig. 6.

Fig. 7.

FIG. 1 is a perspective view of a floodlight showing our new design.

FIG. 2 is a front elevational view thereof.

FIG. 3 is a side elevational view thereof.

FIGS. 4 and 5 are front elevational views of additional embodiments of the design.

FIGS. 6 and 7 are respectively a front elevational view and a top plan view of a further embodiment of the design.

FIG. 8 is a front elevational view of a further embodiment of the design.

The luminaire in the embodiments shown in FIGS. 4-8 are identical to the luminaire of the first embodiment.

The rear of the luminaire housing is flat and plain.

We claim:

The ornamental design for a floodlight, as shown and described.
